INTERNAL COMBUSTION ENGINE

Lionel M. Woolson, Detroit, Mich., assignor to
 Packard Motor Car Company, Detroit, Mich.,
 a corporation of Michigan

Application September 14, 1929
 Serial No. 392,629

9 Claims. (Cl. 123—145)

This invention relates to internal combustion engines and more particularly to devices, known as glow plugs, for assisting the combustion of fuel charges in engines of the type in which ignition occurs through compression.

Glow plugs are especially useful for assisting the starting of Diesel engines, or engines of the Diesel type, in which ignition is caused by compression. In such devices, a resistance wire, anchored at one end to the electrode and at the other end to the body, is usually placed in a relation such that the incoming fuel is sprayed thereagainst and thus atomized to a greater extent than it would be ordinarily. Furthermore, such resistance wire produces a certain degree of heat within the combustion chamber in which the fuel charge is compressed. As the voltage which is usually supplied to glow plugs is necessarily small, the resistance wire must likewise be small to produce the maximum heat.

Diesel engines ordinarily operate at a compression of approximately 500 pounds per square inch in the combustion chamber, so that the explosive shocks and the vibrations caused by explosions are more noticeable than with engines in which the compression is approximately 150 pounds per square inch in the combustion chamber. Furthermore, with engines in which the liquid fuel is sprayed into the combustion chamber against the glow plug, it will be seen that the heat is centralized upon the glow plug, and that it will therefore develop a higher temperature than any of the other elements adjacent thereto. It therefore follows that when the resistance wire of the glow plug is connected with a source of electric supply, that the heat is such as to cause an extreme expansion of both the glow plug wire and electrode with the result that considerable difficulty has been encountered because of breakage of the wire at its point of attachment with the electrode. Such breakage being caused by expansion of the associated metals, causing loosening of the connections, and also by the vibration and fuel pressure causing bending movements of the resistance wire at its points of connection. Furthermore, the high temperature developed within the combustion chamber of an engine of this type is ordinarily such that the incandescent wire of the glow plug will be maintained in a glowing condition even when the connection from the source of electric supply thereto has been switched off, and the above related undesirable conditions will still exist.

An object of my invention is to increase the life of glow plugs by associating the resistance

wire with the electrode in a manner gradually reducing the temperature thereof in a direction toward its point of attachment thereto.

Another object of my invention is to provide a glow plug for internal combustion engines in which the resistance wire is associated and attached to the electrode in a rugged manner such that a relatively long life thereof is assured.

Another object of my invention is to provide a glow plug for internal combustion engines in which the resistance wire is formed in a manner so that fuel can be sprayed intimately with a large incandescent surface.

A further object of my invention is to provide a glow plug for internal combustion engines in which an electrode is secured in insulated relation to a carrier body through a novel form of connecting means.

Still another object of my invention is to provide a glow plug for internal combustion engines which will stand many hours of use with an internal combustion engine without disarranging the relative positions of the component elements.

These and other objects of the invention will appear from the following description taken in connection with the drawing, which forms a part of this specification, and in which:

Fig. 1 is a medial sectional view of a glow plug incorporating my invention,

Fig. 2 is a side elevational view of the same,

Fig. 3 is a sectional view of the glow plug taken on line 3—3 of Fig. 1, and

Fig. 4 is a fragmentary sectional view of one end of the glow plug illustrating the manner in which the inner coil of the resistance wire is associated with the electrode.

Referring now to the drawing by characters of reference, the core or electrode of the glow plug consists of a cylindrical portion 10, an enlarged portion 11 forming a shoulder 12, and a tapered portion 13 terminating in a head 14. A terminal member 15 is arranged at one end of the electrode and is retained thereon by a flanged end 16. Surrounding the electrode intermediate the terminal member 15 and the shoulder 12 is a cylindrical insulating collar 17 preferably formed of mica, while insulating means 18, consisting of mica discs, surrounds the end of the collar adjacent the shoulder 12. A plurality of mica discs 19 surround the collar 17 and extend intermediate the terminal member 15 and the supporting structure for the electrode.

The supporting structure for the electrode consists of a metal body 20, a wedge nut 21, and a tapered sleeve 22. The tapered sleeve surrounds

the collar 17 and in turn is surrounded by the nut 21 which is provided with a tapered interior surface adapted to cooperate with the tapered exterior surface of the sleeve 22. The tapered nut 21 is arranged to be screwed into one end of the body 20. In this manner the sleeve 22 can be drawn against the insulating discs 18 tightly pressing them against the shouldered portion 12 of the electrode and as the mica discs 19 extend intermediate the sleeve 21 and the terminal 15, the electrode is thereby held securely with the housing. A copper gasket 9 is compressed intermediate the inner end of the nut and a shoulder portion of the body.

15 The body is provided with an exteriorly threaded end which is adapted to be screwed into an aperture in the wall of a cylinder of an internal combustion engine. The other end of the body is formed with flat surfaces such that a wrench can be applied thereto for screwing the body into and out of the aperture in the cylinder wall. The body 20 is hollow and is of an interior diameter considerably greater than the diameter of the enlarged portion of the electrode which extends therein. The tapered portion of the electrode projects through the end of the housing and a resistance wire 23 is associated with the electrode and with the body. One end 24 of the resistance wire extends through a diagonally extending opening 25 in the enlarged portion 11 of the electrode and is homogeneously secured at its end to the electrode, as shown at 26, by welding or some similar securing means. A plug 27 extends transversely through one end of the section 11 of the electrode and is arranged so that it will wedge a portion of the resistance wire, extending through the diagonal slot, firmly against the electrode. The other end of the resistance wire extends into a recess 27' in the end of the body 20 and is secured therein by the plug 28 which projects into the recess and switches the wire against the body.

40 The resistance wire 23 is formed in two spaced nesting coils, a portion of each of which surround the tapered portion of the electrode and the inner coil 29 being wound closely around the projecting end of the electrode. The convolutions of the inner coil of the wire become relatively closer together toward the head of the electrode so that two or three convolutions will tightly encircle the tapered end of the electrode in a close relation, and will be maintained in such position axially by the electrode head 14. Such convolutions then continue in increasing diameter and project over and beyond the end of the electrode head where they merge into the exterior coil portion 30 of the wire structure. The central convolution of the outer coil is largest and the convolutions gradually reduce in diameter therefrom. It will be understood that the terminal 15 is adapted to be connected to a source of electrical supply, one terminal of which is grounded, and that the body 20 is screwed into the wall of the cylinder so that the portion of the electrode and the resistance wire projecting beyond the end of the body will lie interiorly of the cylinder of an internal combustion engine. It will be seen that one end of the wire is grounded through being attached to the body 20 while the other end of the wire is connected to the source of the electrical supply by a suitable wiring including a switch mechanism, not shown, connected to the terminal 15.

70 Ordinarily, glow plugs are energized only in starting an engine, however, they may also be used while the engine is in operation if desired.

75 When in contact with the source of electrical sup-

ply the resistance wire 23 produces heat, and spraying of liquid fuel thereagainst materially assists in vaporizing the fuel, thereby promoting starting the engine. Such heat also assists in raising the temperature within the cylinder. As Diesel type engines, with which this invention is particularly adapted to be associated, usually operate at a high compression, approximately 500 or more pounds per square inch in the combustion chamber, and the fuel is injected at a high pressure, usually approximately 2,000 or more pounds, concentration of the fuel upon the resistance wire and the high compression pressure, will maintain the resistance wire in a glowing condition even when the connection with the source of electrical supply is switched off. It will, therefore, be seen that the resistance wire is subjected to intense heat during starting or running of the engine, and that such heat centralizes upon the point of attachment with the electrode.

90 Glow plugs heretofore known to me have failed after short usage, principally because of the breakage of the resistance wire at the point of its connection with the electrode. This breakage is caused by the wire temperature and vibration, 100 the temperature of the wire being substantially maximum at the point of its attachment to the electrode permits breakage by bending moments resulting from vibration. This breaking condition is not so marked with the wire at its attachment to the body because of the high heat differential which will cause an increasing decrease in the wire temperature approaching the connection. It will be seen that I have provided an association of a resistance wire with an electrode such that 110 the wire temperature gradually decreases toward the end attached to the electrode and in which vibration at the connection is substantially eliminated. The manner of fastening the wire extending through the opening in the electrode by wedging and welding is also of material assistance in preventing separation of the wire from the electrode.

115 It will be seen that I have provided a highly efficient structure which is simple in form, and 120 which can be readily assembled when manufacturing. It also will be seen that the resistance wire is such that it will withstand extensive use with engines of the Diesel type, and without increasing its size or the voltage required to produce 125 the requisite heat.

130 While a specific embodiment of the invention has been herein described, which is deemed to be new and advantageous and may be specifically claimed, it is not to be understood that the invention is limited to the exact details of the construction, as it will be apparent that changes may be made therein without departing from the spirit or scope of the invention.

135 What I claim is:

1. In a glow plug for internal combustion engines having a body and an electrode projecting from the body, the projecting end of the electrode being formed with a head, heating means comprising a resistance wire secured at one end to 140 the electrode and secured at the other end to the body, the portion of the wire adjacent the end secured to the electrode being wound closely around and engaging against the projecting end of the electrode in convolutions which are closer 145 toward the electrode head.

2. In a glow plug for internal combustion engines having a body and an electrode carried by and insulated from the body, heating means comprising a resistance wire rigidly secured at one 150

- end to said electrode and at the other end to the body, said wire being coiled about and closely engaging said electrode from its point of attachment thereto for an appreciable distance, and the 5 remainder of said wire forming the major incandescent portion of the glow plug. 3. In a glow plug for internal combustion engines having a body and an electrode insulated from the body, heating means comprising a 10 resistance wire, one portion of the wire being attached to the body and another portion of the wire being coiled against the electrode and secured thereto, the wire intermediate said portions forming an incandescent section which is coiled 15 away from the end of the electrode in convolutions increasing in diameter. 4. In a glow plug for internal combustion engines having a body and an electrode insulated from the body, heating means comprising a resistance wire, one end of the wire being secured to the body, and the other end portion of the wire being coiled against the end of the electrode, the major portion of the wire intermediate the body and the electrode forming an incandescent 20 section. 5. A glow plug for internal combustion engines having a body and an electrode projecting beyond one end of the body, the projecting end of said electrode terminating in a head, heating means comprising a resistance wire fixed at one end to the body and at the other end to the electrode adjacent the body, said wire comprising an interior coil, surrounding and bearing against the electrode between the end connection thereto and 25 the head, and an exterior coil between the head and the end connection to the body spaced from the interior coil.
6. A glow plug for internal combustion engines having a body and an electrode insulated and projecting from the body, an ignition element comprising a resistance wire formed in two nested coils, the inner coil of said wire encircling and closely engaging the projecting end of the electrode, one end of said wire being secured to the electrode and the other end of the wire being secured to the body. 7. A glow plug for internal combustion engines having a body and an electrode insulated and projecting from the body, an ignition element comprising a resistance wire formed in two spaced coiled portions encircling and projecting beyond the projecting end of the electrode, the ends of said wire being secured one to the body and the other to the electrode. 8. In a glow plug for internal combustion engines having a body and an electrode extending from the body, a heating element comprising a resistance wire formed with two nested coiled portions, the outer of which is openly wound, the inner coiled portion of the wire surrounding and extending beyond the projecting end of the electrode and the ends of the wire being secured one to the electrode and the other to the body. 9. In a glow plug for internal combustion engines having a body, an electrode having intersecting apertures therethrough, a resistance wire having one end secured to the body and the other end extending through one of the apertures, and a pin extending through one of the apertures in the electrode, said pin wedging the wire in the aperture with the electrode.
